US0D1071732S

(12) **United States Design Patent** (10) **Patent No.:** **US D1,071,732 S**
(45) **Date of Patent:** **** Apr. 22, 2025**

(54) **FLUID DISPENSER**

(71) Applicant: **Aptar Radolfzell GmbH**, Radolfzell (DE)

(72) Inventor: **Karl Tempfli**, Gottmadingen (DE)

(73) Assignee: **Aptar Radolfzell GmbH**, Radolfzell (DE)

(**) Term: **15 Years**

(21) Appl. No.: **29/870,536**

(22) Filed: **Jan. 30, 2023**

(51) LOC (15) Cl. **09-07**

(52) U.S. Cl.

USPC **D9/448; D9/683**

(58) **Field of Classification Search**

CLAIM

The ornamental design for a fluid dispenser as shown and described.

DESCRIPTION

FIG. 1 is a perspective view of a fluid dispenser showing my new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines illustrating portions of the fluid dispenser are for environmental purposes only and form no part of the claimed design.

1 Claim, 7 Drawing Sheets
